UNITED STATES PATENT OFFICE.

JEREMIAH ANTHONY SMOLICK, OF HONOLULU, TERRITORY OF HAWAII.

INDICATING AND SALVAGING DEVICE FOR SUBMARINE BOATS.

1,243,997.

Specification of Letters Patent. Patented Oct. 23, 1917.

Application filed October 2, 1916. Serial No. 123,288.

To all whom it may concern:

Be it known that I, JEREMIAH ANTHONY SMOLICK, a citizen of the United States, residing at Honolulu, Territory of Hawaii, 5 have invented certain new and useful Improvements in Indicating and Salvaging Devices for Submarine Boats; and I do declare the following to be a full, clear, and exact description of the invention, such as will 10 enable others skilled in the art to which it appertains to make and use the same.

This invention relates to new and useful improvements in automatic indicating and salvaging attachments for submarine boats 15 and the primary object of the invention is to provide a device of this character which is adapted to be secured to the superstructure of a submarine boat and which comprises buoys which are automatically released from the boat if the same is unable 20 to return to the surface and thus will indicate the boat's position.

A further object of this invention is to provide a device of this character which is 25 provided with indicating buoys, said buoys also carrying a wire cable, which is passed through a shackle secured to the hull of the boat so that when the buoys float to the surface, they will carry the cable and hence 30 the lifting of the boat will be comparatively a simple matter.

Still another object of this invention is to provide a device of this character which is 35 provided with means that are set when the submarine boat dives, and will automatically release the buoys at a predetermined time after diving so that there will be absolutely no chance of the position of a crippled boat 40 not being indicated, owing to accident to the crew.

Another object of the invention is to provide this attachment with supplemental releasing means for the buoys, so that if the first means fails to act owing to the fact that 45 a certain amount of water may perhaps enter the casing, the supplemental releasing means will be operated by the water, and hence release the buoys.

A further object of the invention is to 50 provide a device of this character which is easily and simply constructed, inexpensive to manufacture, and one which will be very efficient in operation.

With these and numerous other objects in 55 view, my invention consists of the novel features of construction, combination and arrangement of parts which will be hereinafter

referred to and more particularly pointed out in the specification and claims.

In the accompanying drawings: 60

Figure 1 is a partial transverse section of the upper portion of a submarine boat showing my device applied thereto;

Fig. 2 is a similar view showing the parts in released position; 65

Fig. 3 is a view showing the operation of the supplemental releasing means;

Fig. 4 is a horizontal section taken on the line 4—4 of Fig. 1;

Fig. 5 is a vertical section taken on the 70 line 5—5 of Fig. 4;

Fig. 6 is a vertical section taken on the line 6—6 of Fig. 4;

Fig. 7 is a vertical section taken on the 75 line 7—7 of Fig. 4;

Fig. 8 is a vertical section taken on the line 8—8 of Fig. 4; and

Fig. 9 is a diagrammatic view showing the connection for the circuit closing device.

Referring to the drawings, I have shown 80 a partial transverse section of a submarine boat of the conventional type which is designated by the numeral 1, and which is provided with a superstructure 2 in which my improved automatic indicating and salvaging attachment is positioned. This attachment comprises buoys 3 and 4, which buoys are positioned in spaced relation along the boat, any desired number of pairs being used according to the length, or type of submarine boat to which this attachment is applied. For the sake of brevity, I will specifically describe only one pair of buoys and the means by which they are detachably secured to the boat. 85

The buoys 3 and 4 are positioned in the superstructure 2 of the boat in spaced relation on either side of the center of the same, and directly in the center between the said buoys is a shackle 5, which is bolted to the upper portion of the hull of the boat. These buoys 3 and 4 may be formed of any desired material, and they are detachably connected to the boat in a manner to be hereinafter more fully described. 95

Positioned adjacent the buoy 4 is a reel 6 which is provided with a spring-brake 7, and on which is wound a wire cable 8. This wire cable 8 has its opposite ends attached to the buoys 3 and 4 as clearly shown in the drawings, and the cable is doubled intermediate its length, so that the doubled portion is wound on the reel. One end of the cable 8 adjacent the buoy 3 is passed through 100

105

110

115

the shackle 5, so that when the buoys are detached from the boat, and the cable is unwound from the reel, the lower end of the same will be positioned through the shackle 5 so that upon lifting the cables, the boat will consequently be raised.

This manner of attaching the cable to the buoys affords an easy and simple manner of providing a raising device. The cables 10 that are wound on the reel are too light to perform the task of lifting the boat, but they are used as messengers, and a heavy wire chain carried by the same through the shackle, and used to raise the boat. It will 15 be obvious that owing to the fact that there are several pairs of buoys positioned along the superstructure of the submarine boat, when the boat is disabled, and is unable to rise to the surface, several cables will be 20 carried to the top by the buoys when they are detached. In this manner the boat may be raised on an even keel without endangering the lives of the occupants, or in any manner endangering the internal machinery.

Secured to the lower surface of the upper portion of the hull of the boat 1 directly beneath the buoys 3 and 4 is a casing 9, that extends across the boat so that it will be positioned beneath each of the buoys. This 25 casing 9 has a false bottom 10, and positioned between the false bottom 10 and the bottom of the casing 9 are a plurality of batteries 11 which are used in the operation of the detaching means of said buoys. The buoys 3 and 4 have downwardly projecting 30 stems 12, that project through the hull of the boat and are disposed within the casing 9, when the buoys are secured or attached in the superstructure. The projecting stems 40 12 are surrounded by tubular casings 13, which are water-tight, and which have flared open upper ends secured around the openings in the hull through which the stem is passed. The lower ends of these casings 45 are closed, and the connection between the upper ends of the same and the hull is made water-tight, so that no water will be able to leak into the casing 9.

Positioned within the casing 9 and centrally between the tubular casings 13, is a vertical shaft 14 upon which is mounted a substantially U-shaped frame 15 having laterally projecting portions 16 with upturned ends 17, that are disposed parallel with the said frame. The closed end of the frame 15 surrounds the vertical shaft or bar 14 and is slidably mounted thereon, and mounted on the lower end of the bar is a coil spring 18, which has its upper end positioned 55 against the closed end of the frame. This coil spring 18 is adapted to be compressed by moving the frame 16 downwardly, and the same may be held under pressure by the insertion of a locking pin 19 between the 60 closed end and the bar, which will securely

hold the frame in position against the tension of the spring. This pin 19 is formed of salammoniac or any other desired material that is adapted to dissolve when placed in water. The purpose of the provision of a 70 pin of this character to hold the frame 15 against the tension of the spring, is so that should water accidentally enter the casing 9, and surround the pin 19, the same will dissolve and the frame 15 will consequently 75 be forced upward by the expansion of the said spring. The purpose of this upward movement of the frame will be hereinafter more fully described.

Positioned between the tubular casings 80 13 within the casing 9 are a pair of brackets 20, which have upright sides 21 with alining openings 22 therethrough. Positioned through the alining openings 22 of these sides are rods or bars 23, which are slidably 85 mounted, and which are provided with notches 24 adjacent one end. Portions of the rods 23 between the sides of the brackets are surrounded by coil springs 25, and secured to one of the sides 21 of the brackets 90 90 are pivoted levers 26, which are adapted to form locks for the rods, when the same is forced outwardly through the brackets against the tension of the springs 25, and the notches 24 therein will receive said 95 levers. Each lever 26 has a projecting portion 27 that extends outwardly, and is disposed substantially in alinement with the projecting portion of the lever on the opposite bracket. Each of the brackets 20 is 100 provided with a rod, and the above described attachment, and these rods have their outer ends attached to one end of rock shafts 28 which are journaled through the sides of the tubular casings 13 in stuffing boxes as 105 shown at 29.

The rock shafts 28 have their ends positioned within the tubular casings bent upwardly as shown at 30, and have their extremities forked as shown at 31, the forked 110 portions being adapted for engagement with notches 32 in the lower ends of the stems 12 of the buoys. The rock shafts 28 are journaled through the sides of the castings in stuffing boxes, so that there will be no chance 115 of any water leaking through the openings into the casing 9. These shafts are bent adjacent their opposite ends, and the ends of the same are connected with the sliding bar, and the lower ends of the stems respectively. 120 When these parts are in operative position, the sliding bars 23 that are disposed in the brackets 20 are forced through said brackets so as to compress the springs 25, and the locking lever 26 is swung down in operative position. This will pull the connected 125 ends of the rock shafts 28 inwardly, and consequently the opposite forked ends of these shafts will be moved into operative position with the lower notched ends of the 130

5 stems 12 of the buoys. In this manner, the buoys will be locked into engagement with the boat, and will be prevented from being detached therefrom when the submarine boat is submerged. The locking levers 26 will have their projecting portions 27 disposed in alinement for a purpose to be hereinafter more fully described. These projecting portions will be positioned with their ends 10 adjacent each other, a certain amount of space being left between their ends.

15 The upturned extremities 17 of the frame 15 will be positioned substantially in the space between the ends of the levers 26, and 15 slidably mounted on their ends is a trip-plate 33 which is provided with a pair of openings 34 adapted to receive therein, the ends 17 of the frame. This plate will easily slide up and down on the ends, which will form 20 guides for its vertical movement. The plate 33 is so positioned that it will be disposed directly beneath the projecting end portions 27 of the locking levers 26, so that any upward movement of this plate will consequently raise the locking levers 26 and release the sliding bar 23.

25 As soon as the trip-plate 33 is raised, and the locking means are disengaged from the notches in the sliding bars 23, these bars owing to the expansion of the springs 25 will be forced outward, and consequently they will move the rock shafts 28. Upon the movement of the connected end of these shafts caused by the sliding bars, the opposite ends of the shafts will be detached from the lower ends of the stems 12 of the buoys, and consequently the buoys will be freed from the boat and will rise to the surface. Sufficient space is left between the stems 12 40 and the casings 13 to allow the end of the rock shafts positioned therein to move freely, so that the forked ends of the same may be easily withdrawn from the notches in the stems upon very slight movement.

45 The primary means for raising the trip 33 to release the buoys from the boat, comprises a solenoid 35 that is placed on the bottom 10 of the casing 9, directly beneath the trip. This solenoid is operatively connected 50 with the batteries 11 in the bottom of the casing, and positioned in the same circuit therewith is a clock 36 that is provided with a circuit closer 37. These parts are so arranged that when the boat dives, the circuit closer on the clock is set for a certain time, and when the time is reached, the hands of the clock will close the circuit, and consequently operate the solenoid. This will cause the core 38 of the solenoid to move vertically upward and to force the trip-plate 33 60 upwardly on the guide 17 of the frame, to raise the locking levers 26. This operation will release the buoys from the boat automatically.

65 From the above described construction

and arrangement of parts, it will be seen that it is a comparatively simple matter to release the buoys from the boat automatically at a predetermined time. By the use of a circuit closer of this character, it will be 70 certain that the buoys will be released, without any manual operation, after a certain length of time the boat is beneath the surface. This obviates all danger of the inability of the crew to release the indicating 75 buoys owing to some accident of the machinery of the boat which will render them unconscious and therefore unable to operate the salvaging device.

In case of any accident where the water 80 should force an entrance into the casing 9, the batteries 11 disposed in the bottom thereof would consequently become inoperative, and this detaching means would not operate. To overcome this objection, I have provided 85 a supplemental detaching means, which has been hereinbefore described in detail, and which comprises the slidable frame 15 that is secured under spring tension by the sal-ammoniac pin 19 on the vertical bar 14. If 90 water should enter the casing 9 and render the batteries 11 inoperative, the solenoid 35 consequently would not operate to move the trip 33 upwardly, but owing to the fact that the frame 15 upon which the trip is mounted 95 and supported being held under spring tension, when the water surrounds the locking pin, and the said pin dissolves, the spring 16 will expand and consequently raise the frame 15 and the trip-plate 33 disposed 100 thereon. This operation will raise the locking levers 26, and release the buoys from the boat in the manner hereinbefore fully described.

This supplemental detaching means affords a safe and absolutely certain operation of this attachment, no matter what the circumstances under which the same is applied. The locking pin 19 may be formed of any desirable material that will readily 105 dissolve when surrounded by water, so as to allow the frame 15 to move upwardly. The trip that is positioned on the upturned ends 17 of the arms of the frame 15 is normally positioned at the lower end of the 110 same, so that upon any upward movement of the supporting frame, the trip will be raised and the locking levers 26 released. From the arrangement above described, it will be obvious that the primary releasing 115 means may be operated, that is the solenoid, and the trip moved upwardly to release the buoys without disturbing the supplemental detaching means. The trip-plate 33 will slide up and down on the ends 17 of the 120 frame, without moving the frame, or releasing the spring 18.

The buoy 4 that is disposed within the superstructure of the boat is formed with a central hollow portion 40, that has mounted 130

therein a reel 41 upon which is adapted to be wound a coil of telephone wire 42. The stem 12 of the buoy 4 is formed with a tubular passage 43 that extends from its upper end to a point adjacent its lower end and then projects laterally outward until it terminates in an opening 44 through the side of the same. The telephone wire from the reel is passed downwardly through this passage and out through the side of the stem, and this is extended through the side of the tubular casing 13, where it is attached to a telephone set 45. By this means, when the buoys are released and are picked up by a rescuing ship, telephoning communication may be immediately established between the crew of the wrecked submarine and the rescuing boat.

I claim:—

- 20 1. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a trip to release the lock, means to operate the trip whereby the buoy is released, and a supplemental trip operating means operable when surrounded by water.
- 25 2. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a trip to release the lock, means to automatically operate the trip whereby the buoy is released, and a supplemental trip operating means operable when surrounded by water.
- 30 3. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a trip to release the lock, means to operate said trip at a predetermined time whereby the buoy is released, and a supplemental trip operating means operable when surrounded by water.
- 35 4. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a trip to release the lock, means to operate said trip at a predetermined time whereby the buoy is released, and a supplemental trip operating means operable when surrounded by water.
- 40 5. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a trip to release the lock, means to operate said trip at a predetermined time whereby the buoy is released, and a supplemental trip operating means operable when surrounded by water.
- 45 6. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a trip to release the lock, means to operate said trip at a predetermined time whereby the buoy is released, and a supplemental trip operating means operable when surrounded by water.

7. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a trip to release the lock, circuit controlled means for operating said trip at a predetermined time whereby the buoy is released, and a supplemental trip operating means operable when surrounded by water.

8. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a plate disposed beneath said lock, and movable to release the same, a solenoid disposed beneath said plate, circuit controlled means to operate said solenoid to move the plate at a predetermined time, and a supplemental trip operating means operable when surrounded by water.

9. An indicating and salvaging device for submarine boats comprising a buoy having a stem projecting through the hull of the boat, a cable connecting said boat and buoy, means for detachably locking said buoy to the boat including a movable member engaging the stem, a self-actuated member connected with the movable member, a lock for said self-actuated member, a plate disposed beneath said lock, and movable to release the same, a self-actuated plate support normally locked against movement, circuit controlled means moving said plate at a predetermined time without movement of the support, and supplemental means for releasing said support when surrounded by water to move the plate.

10. An indicating and salvaging device for submarine boats comprising a buoy having a stem projecting through the hull of the boat, a cable connecting said boat and buoy, means for detachably locking said buoy to the boat including a casing surrounding said stem, a rock shaft journaled through said casing and having one end connected with the stem, a self-actuated member connected with the opposite end of said shaft, a lock for said member, and an automatically operated trip to release the lock whereby the shaft is disconnected from the stem and the buoy is released.

11. An indicating and salvaging device for submarine boats comprising a buoy having a stem projecting through the hull of the boat, a cable connecting said boat and buoy, means for detachably locking said buoy to the boat including a casing surrounding said stem, a rock shaft journaled through the casing and having its inner end forked, said stem having its lower end notched and adapted to receive said forks when in locked

position, a self-actuated member connected with the opposite end of said shaft, a lock for said member, and an automatically operated trip to release said lock whereby the 5 shaft is rocked and its forked end is disconnected from the stem to release the buoy.

9. An indicating and salvaging device for submarine boats comprising a buoy having a stem projecting through the hull of the 10 boat, a cable connecting said boat and buoy, means for detachably locking said buoy to the boat including a rock shaft detachably connected with said stem at one end, a bracket, a spring actuated sliding bar in 15 said bracket connected with the other end of said shaft and adapted to rock the same, a lock to hold said bar under spring tension, and an automatically operated trip to release said lock.

20 10. An indicating and salvaging device for submarine boats comprising a buoy having a stem projecting through the hull of the boat, a cable connecting said boat and buoy, means for detachably locking said 25 buoy to the boat including a rock shaft detachably connected with said stem at one end, a bracket, a spring actuated sliding bar in said bracket connected with the other end of said shaft and adapted to rock the same, 30 a pivoted lever adapted for engagement with a notch in said bar when the spring is compressed, and an automatically operated trip disposed beneath said lever and adapted to move the same from the notch to release 35 said bar.

11. An indicating and salvaging device for submarine boats comprising a buoy having a stem projecting through the hull of the boat, a cable connecting said boat and buoy, means for detachably locking said 40 buoy to the boat including a movable member engaging the stem, a self-actuated member connected with the movable member, a lock for said self-actuated member, a sole- 45 noid disposed beneath said plate, and circuit controlled means to operate said sole-noid to move the plate at a predetermined time.

12. An indicating and salvaging device 50 for submarine boats comprising a buoy having a stem projecting through the hull of the boat, a cable connecting said boat and buoy, means for detachably locking said buoy to the boat including a movable member 55 engaging the stem, a self-actuated member connected with the movable member, a lock for said self-actuated member, a vertical shaft, a spring actuated plate supporting frame slidably mounted on said shaft, 60 a pin to hold said frame under spring tension, said pin being adapted to dissolve when surrounded by water whereby the

frame and plate will be moved by the expansion of the spring.

13. An indicating and salvaging device 65 for submarine boats comprising a pair of spaced buoys detachably connected with the boat and disposed in the superstructure of the same, a shackle positioned between said buoys, a cable passing at one end through 70 said shackle and having its opposite ends secured to said buoys, said cable being doubled upon itself substantially midway its ends, and a reel upon which the doubled portion of said cable is wound, but unsecured. 75

14. The combination with a submarine, of a buoy, a cable to be carried from the submarine to the surface of the water by said buoy, means for normally connecting said 80 buoy with the submarine, time controlled means for releasing said connecting means automatically when the submarine has been submerged a predetermined time, and water-operated means for automatically releasing 85 said connecting means in case said time controlled releasing means should fail to operate.

15. The combination with a submarine, 90 of a buoy, a cable to be carried from the submarine to the surface by said buoy, means for normally connecting said buoy with the submarine, time controlled means for automatically releasing said connecting means when the vessel has been submerged 95 a predetermined length of time, and additional means for releasing said connecting means and including a prime mover and a soluble abutment for normally preventing movement thereof, said abutment being located in a substantially water-tight chamber which, however, may fill gradually with the water in case the vessel is submerged an unusual length of time. 100

16. The combination with a submarine, 105 of a buoy, a cable to be carried from said submarine to the surface of the water by said buoy, means for normally connecting said buoy with the submarine, and means for releasing said connecting means including a prime mover, a soluble abutment for normally preventing movement thereof, and a substantially water-tight chamber in which said abutment is located, said chamber being permitted to fill slowly with water in case 110 the vessel is submerged an unusual length of time. 115

In testimony whereof I have hereunto set my hand in the presence of two subscribing witnesses.
